J. Hyde,

Wash-Board,

No 11,426,

Patented Aug. 1, 1834.

UNITED STATES PATENT OFFICE.

JOSEPH HYDE, OF NEW YORK, N. Y.

WASHBOARD.

Specification of Letters Patent No. 11,426, dated August 1, 1854.

To all whom it may concern:

Be it known that I, JOSEPH HYDE, of the city and State of New York, have invented certain Improvements in Washboards; and 5 I do hereby declare that the following is a full, clear, and exact description of the same, reference being had to the annexed drawings, making a part of this specification, in which—

10 Figure 1 is a perspective view of the "board" with the "rubber" combined with it. Fig. 2 is a longitudinal edge section. Fig. 3 is a perspective view of the rubber detached from the wash board, the opposite side being shown to that represented in Fig. 1.

The same letters refer to like parts in each of the figures.

The nature of my invention consists, 20 firstly, in forming the surface of a wash board of a congeries of projections or knuckles, prominent and distinct (although not necessarily disconnected), and of a substance in itself elastic or semi-elastic.

25 Secondly, my invention consists in combining in a peculiarly handy and simple way, with such a "wash board" a "rubber" which may be a scouring brush with elastic knuckles on its reverse side, and the 30 "rubber" may be so arranged as to present either surface to the wash board at the will of the operator.

The construction is as follows:

A, Fig. 1, is a frame of any usual or 35 convenient form holding a panel B of wood or metal, and rather thin as compared with its equivalent in an ordinary wash board. This panel is pierced with holes, through which are forced short round ended cylinders of 40 vulcanized caoutchouc or gutta percha of greater diameter than the holes, after which the extremities of these cylinders will expand against those adjoining and assume the form of round headed rivets. See Fig. 45 2; together constituting a series of elastic knuckles over the whole surface of the wash board.

C is the "rubber," the brush side exposed (the reverse side being shown at Fig. 3) and 50 is connected to the board at (a) by the intermediate "toggle" links or levers (b) and so that at the trunnions (c) the "rubber" may revolve or "swivel" between the ends of the toggle levers.

55 It will now be seen that a person standing at the head of the board, which may be of

the ordinary size, and the feet of the board resting upon the bottom of a wash tub in the usual way, the article to be washed being placed upon the face of the board and the "rubber" being raised and placed upon the article, the edge or a fold of the article being pinched against the lower edge of the "rubber" by the fingers and the rubber itself being firmly grasped by the whole hand or hands, it will be seen that the article may be thoroughly rubbed with any desired pressure, the toggles allowing the rubber to move up and down squarely over the board, and without the knuckles of the hands being called into play at all, and articles of the coarsest or most delicate texture may be perfectly treated in a way to correspond to its nature without the employment of a cumbersome washing machine on the one side 60 or any abrasion of the fingers on the other. The rubber however may be moved up into the recess (d) out of the way if desired as occasion may require. The opposite sides of the board are alike and either may alike 65 be employed, the rubber it will be obvious on inspection of the figures being capable of passing over the head of the board to either side of it indifferently, and would present precisely the same appearance and mode of 70 operation.

The knuckles or projections can also be formed in another way, although substantially the same in nature; in this latter mode of constructing or forming my yielding, knuckled, rubbing surfaces for wash boards, the difference being that in lieu of the india rubber rivets, I form the knuckles by threading through and through the panel or face of the board, shoemaker fashion, 75 india rubber cord, or even cotton cord which proves a very cheap and serviceable substitute of cotton cord covered or coated with caoutchouc may be used. The cord should be evenly twisted and drawn in taut, and of course, fastened by a knot or any convenient means at each extremity. All things considered, I prefer this modification to the other.

The effectiveness and beauty of operation 80 of my device for its purpose, both as regards the peculiar character of the rubbing surfaces and the convenient mode of attachment and action of the "rubber" will be seen without any lengthy expatiation.

I am aware that cushions or pads of india rubber have been used in "washing ma-

chines" for "rubbers" acting on a common board (which formed an item in such machines), but it is not the material so much as the form under which it is brought in action. Thus I find cotton nearly or quite as good as india rubber for material. I find no form of surface however to compare with the "knuckle" for rubbing and cleansing textile substances.

10 Having thus fully described the nature of my invention what I claim as new and desire to secure by Letters Patent is—

1. The employment of the elastic or semi-elastic "knuckles" each distinct but the

whole forming a compact series over the 15 whole rubbing surface of a wash-board of any usual or convenient form by methods substantially as described.

2. I claim in combination therewith the rubber connected to it substantially as de- 20 scribed so as to reverse to either side of the "board" and "swiveling" if desired in its own immediate bearings for the purpose de- scribed.

JOSEPH HYDE.
